DE WITT C. LAMBSOHN

DOORSTOP HOLDER

Filed March 8, 1924

19 Inventor
Delville C. Lambson
of Seymour Town
attg.

UNITED STATES PATENT OFFICE.

DE WITT C. LAMBSON, OF WALLINGFORD, CONNECTICUT.

DOORSTOP HOLDER.

Application filed March 8, 1924. Serial No. 697,768.

To all whom it may concern:

Be it known that I, DE WITT C. LAMBSON, a citizen of the United States, residing at Wallingford, in the county of New Haven 5 and State of Connecticut, have invented a new and useful Improvement in Doorstop Holders; and I do hereby declare the following, when taken in connection with the accompanying drawings and the characters of 10 reference marked thereon, to be a full, clear, and exact description of the same, and which said drawings constitute part of this application, and represent, in—

Fig. 1 a perspective view of a door-stop holder constructed in accordance with my 15 invention and shown as applied to a garage door.

Fig. 2 an end view, showing the parts when the door is in the open position.

Fig. 3 a similar view, showing the parts 20 when in position for closing the door.

Fig. 4 a broken side view of the tube and its supporting-bracket.

Fig. 5 a broken plan view of the operating-rod detached.

This invention relates to improvement in door-stop holders, that is, devices particularly adapted for use on garage doors for holding them in an open position, the object 20 of the invention being to provide a simple construction whereby the door will be positively held in an open position and conveniently released when it is desired to close the door, and the invention consists in the 35 construction as hereinafter described and particularly recited in the claims.

In carrying out my invention, I employ a long tube 10, channel or support cut away at its outer end to leave a finger 11, which is adapted to be pivotally connected with an arm 12 of a bracket 13 adapted to be secured to the inner face of a door 14 near the upper edge thereof. The tube is formed near its inner end with a transverse notch 15, beyond which the end of the tube is split and the edges 16 and 17 turned downward. Extending through the tube is a rod 18 formed at its outer end with a crank-arm 19, to the outer end of which a chain 20 may be attached, whereby the rod may be rocked. The rod projects beyond the inner end of the tube and is turned backward along one side of the tube, to form a lifting surface 21 and the end curved to form a cam 22. This rod 50 is supported at the inner end of the tube by

a ring 23 mounted in the upper side of the tube, and the tube extends through a keeper 24, of any approved design, having a transverse bar 25 with which the notch 15 in the tube may engage. 60

In the open position, as shown in Fig. 1 of the drawings, the notched end of the tube sets over the bar 25 of the keeper, so as to securely hold the door in its open position, and in this position the lifter 21 rests upon the bar 25 at one side of the tube. When it is desired to close the door, a downward pull upon the chain 20 rocks the rod 18 and forces the lifter 21 downward, so as to raise the inner end of the tube sufficiently to lift 70 it out of engagement with the keeper, and so permit the door to be closed, and in closing, the tube turns in the keeper so as to stand substantially parallel with the door when in its closed position, and in this closed position, the chain 21 hangs downward, close to the door. In opening the door, the tube is drawn outward, and the cam 22, at the end of the rod 18, first strikes the bar 25 of the keeper, so as to easily ride over it and permit the tube to drop down over the keeper when the notch 15 is in line therewith. In opening the door, therefore, no attention need be paid to the door-stop holder, as it is automatic in action, and the only movement necessary to release it is a downward pull upon the chain. 80

It will be seen that the parts are readily formed without machine work, and, consequently, can be produced at a very low cost 90 for manufacture.

I claim:

1. A door-stop holder, comprising a longitudinal support adapted to be pivotally connected at its outer end with a door, and formed near its inner end with a notch, a keeper with which said notch is adapted to engage, and a rod extending longitudinally of said support, said rod formed at its inner end with a lifter crossing the notch in the support, and at its outer end with a crank by which the rod may be rocked. 95

2. A door-stop holder, comprising a tube adapted to be pivotally connected at its outer end with a door, said tube formed near its inner end with a transverse notch, the end of the tube beyond the notch divided and the ends turned downward, a rod extending through said tube and supported therein at its inner end, said rod bent back- 100

110

ward beyond the said notch forming a lifter, and a keeper having a bar with which the notch in the tube engages.

3. A door-stop holder, comprising a tube adapted to be pivotally connected at its outer end with a door, said tube formed near its inner end with a transverse notch, the end of the tube beyond the notch divided and the ends turned downward, a rod extending through said tube and supported therein at its inner end, said rod bent backward beyond the said notch forming a lifter, and its end curved to form a cam, and a keeper having a bar with which the notch in the tube engages.

4. A door-stop holder, comprising a tube, a bracket with which the outer end is pivotally connected, a tube formed near its inner

end in its under-side with a transverse notch, the end of the tube divided and turned downward, a rod extending through said tube and formed at its outer end with a crank-arm, said rod projecting beyond the inner end of the tube and turned backward beyond said notch and terminating in a cam, said rod supported at its inner end by said tube, and a keeper through which the tube extends and with which the notch engages when the door is in its open position.

In testimony whereof, I have signed this specification in the presence of two subscribing witnesses.

DE WITT C. LAMBSON.
